UNITED STATES PATENT OFFICE.

CHARLES J. SLADEK, OF CHICAGO, ILLINOIS.

SIGNAL LIGHT.

Application filed February 13, 1925. Serial No. 9,063.

This invention relates to new and useful improvements in signal lights and more particularly to what will be known as a courtesy light. The main object of my invention is the provision of a light of the above character which is attached to the hood cap of a motor vehicle radiator and preferably adapted for use in signaling drivers travelling in a direction which crosses that of the vehicle to which the light is attached so as to convey to the other driver the intentions of the driver of the vehicle to which the light is attached.

Another object of my invention is the provision of a signal light which is not only used as a direction signal for other motorists, but is also used for illuminating the radiator gauge to ascertain the condition of the cooling fluid in the radiator.

A further object of my invention is the provision of a signal light including novel means for supporting the light in position directly in front of the radiator of the vehicle and in alignment with the gauge attached thereto, together with novel signalling means for conveying the driver's intentions to other drivers approaching a crossing either from the right or the left.

With the above and other objects in view, my invention consists in the novel features of construction and the combination and arrangement of parts to be hereinafter more fully described, pointed out in the claim and shown in the accompanying drawings, in which:

Fig. 1 is a vertical sectional view, parts thereof being illustrated in elevation and showing the application of my device, and

Fig. 2 is a top plan view.

Referring more particularly to the drawings, 1 indicates the top portion of a motor vehicle radiator having the usual cap 2 attached to the filling neck 3. Attached to the filling neck is a clamp 4 carrying an angular bracket 5 which includes a horizontal portion 6 having an opening 7 therein.

My improved signal light includes a bottom plate 8 and a top plate 9, each having an annular flange upon its perimeter which project toward each other when the plates are arranged in an operative position, as shown in Figure 1. The globe 10 includes a rectangular body portion having circular end portions 11 one of which rests upon the bottom plate 8 within the confines of the annular flange of the lower plate. These two

plates 8 and 9 are clamped on to the ends of the globe by means of a bolt 12 having a head 13 upon its upper end and a detachable nut 14 on its lower end, said bolt extending centrally through the plates and through the globe.

The two side faces 15 and 16 are provided with signal indicia, the signal indicia being preferably arranged upon a circular portion 65 as indicated and includes the words "Go" and "Stop", the "Go" being indicated on the side 15 while the "Stop" is indicated on the side 16. The forward or front side of the globe has a circular portion 17 upon which suitable indicia may be placed, such as the name of the motor vehicle or any other indicia desired.

The rear side wall of the globe is provided with an opening 18 which is preferably arranged in alignment with the water gauge 19 attached to the radiator cap 2. An electrical bulb 19 is arranged within the globe and has connections through the wire 20 with the usual lighting circuit of a motor vehicle, in order to illuminate the globe when desired. It will be apparent that the globe 19 is connected to any suitable type of manually operated switch whereby the driver of the vehicle may signal his intentions to other drivers approaching either from the right or left.

The bottom plate 8 rests upon the horizontal portion 6 of the bracket 5 and the bolt 12 extends through this bracket, as indicated in Figure 1, and the plate 8 is further provided with an indentation forming a protrusion 21 which extends into the opening 7 of the bracket 5 for preventing turning movement of the globe when securely bolted to the bracket.

It will be apparent from the forgoing that I have provided a simple and inexpensive signal light which is preferably known as a courtesy light to indicate to drivers of vehicles either approaching from the right or the left, the intentions of the driver of the vehicle to which the light is attached to avoid collisions and serious accidents. The device itself can be manufactured and placed upon the market at a very low cost and is so constructed that it may be quickly and readily attached to the filling spout or radiator cap of any well-known make of vehicle. While the device is extremely useful as a 110 courtesy light, it will also be apparent that the same may be used equally as well for as-

certaining the condition of the water in the radiator through the illumination of the radiator gauge 19.

While I have shown and described the preferred form of my invention, it will be obvious that various changes in the details of construction and in the proportions may be resorted to for successfully carrying my invention into practice without sacrificing any of the novel features or departing from the scope of the appended claim.

Having thus described my invention, what I claim is:

The combination with a filling neck of a radiator of an automobile, of a clamp se-

cured about the filling neck and including a substantially horizontal end portion disposed in a plane above the clamp providing a supporting bracket, a globe supporting bottom plate disposed upon the horizontal end portion and provided with a protuberance, there being an opening formed in the horizontal end portion receiving the protuberance, said protuberance cooperating with the horizontal end portion to prevent rotation of the globe relative to the horizontal portion.

In testimony whereof I affix my signature.

CHARLES J. SLADEK.
